UNITED STATES PATENT OFFICE

167,295

TOY CRADLE

Charles Arliss, New York, N. Y.

Application April 8, 1952, Serial No. 19,255

Term of patent 7 years

(Cl. D34—15)

To all whom it may concern:

Be it known that I, Charles Arliss, a citizen of the United States of America and a resident of the city of New York, in the county of Queens and State of New York, have invented a new, original, and ornamental Design for a Toy Cradle, of which the following is a specification, reference being had to the accompanying drawing, forming a part thereof.

Fig. 1 is a perspective view of the toy cradle showing my new design;

Fig. 2 is a plan view thereof; and

Fig. 3 is a side elevational view thereof.

I claim:

The ornamental design for a toy cradle, substantially as shown.

CHARLES ARLISS.
